UNITED STATES PATENT OFFICE

1,972,104

MOUNTING FOR FLEXIBLE TYPE HOLDING CHASES

Frank H. Poeppelmeier, Dayton, Ohio, assignor, by mesne assignments, to Set-O-Type Manufacturing Company, Cleveland, Ohio, a corporation of Delaware

Application July 18, 1931, Serial No. 551,657

5 Claims. (Cl. 101—415.1)

This invention relates to means for holding a flexible type chase, and particularly a chase having a plurality of tensioning straps, on a suitable support, as for instance, a rotary drum.

- 5 In the accompanying drawing illustrating my invention, Figure 1 is a face view of my improved flexible type chase. Figure 2 is a face view, in modified form, of my flexible type chase. Figure 3 is an end view of one of the type channels shown in Figure 1. Figure 4 is a side view of the same. Figure 5 is an end view thereof showing one method of closing one end of the type channel. Figure 6 is a side view of a type channel, showing another method of closing one of its ends. Figure 15 7 is an end view of the type channel shown in Figure 6. Figure 8 is a side view of a type channel showing another method of closing one of its ends. Figure 9 is an end view of the type channel shown in Figure 8. Figure 10 is an end view 20 of the united type channels shown in Figure 2. Figure 11 is an end view of a chase segment as applied to the supporting member, showing the method of securing it in place. And Figure 12 is a sectional view taken on the line 12—12 of Figure 11 through the locking device.

Referring to the accompanying drawing, the numeral 1 designates a flat, flexible, spring-tempered band, of which three are shown in Figure 1. Type channels 2 formed with slits 3 are adapted to be slid or slipped over the strap bands 1 into juxtaposition to receive type for a desired composition.

The slits 3 in the channels permit them to be easily applied to the strap bands 1, which project through the slits. The composition so set up on this flexible chase may be easily secured to a supporting member or plate by means hereinafter described; and after its present use, the chase may be removed to preserve the composition in a compact space for future use at low cost.

Each type channel may be closed at one end to confine the type, in various ways. Three of those methods are shown.

In Figures 4 and 5 I have illustrated a type channel formed with ears 4, 4 on the end thereof for this purpose. In Figures 6 and 7, ears 5, 5 are punched from the side walls of the channel 2 near one of its ends; and in Figures 8 and 9 ears 6, 6 are punched out and turned downwardly from the top flanges of the channel 2.

As shown at Figure 10, I have provided a modified type channel 7, consisting of channel-shaped members 8, arranged back to back and spot-welded together.

55 The foot portion 9 of each channel member 8

is longer than the top portion 10 so that when they are assembled upon the bands 1, as shown at Figure 10, the former will be brought together to provide a clearance between the adjacent top portions 10, 10.

When thus assembled upon the bands 1, the type will be received between the top portions 10—10 and the vertical walls 11 in the same manner as employed with the channel 2.

Above the foot portions 9, the vertical walls 11 are provided with slots 12, similar to the slots 3 through which the bands 1 pass.

The type chase above described is claimed per se, in my copending application No. 638,702, filed October 20, 1932. The present patent is concerned with means for drawing such a chase taut upon the supporting member and effectively holding it thereto during operation, as about to be described.

Each end of the bands 1 is provided with key-hole slots 13, 13 to receive therein, when assembled upon a supporting member 14, a fixed stud 15 at one end and an adjustable stud 16 at the opposite end. (See Figure 11).

The fixed stud 15 is provided with a shoulder 17 to receive thereon, between the face of the supporting member 14 and a flat head 18 on the stud, one end of one of the bands.

The adjustable stud 16 is likewise shouldered and has a lower threaded end 19 that is received by a tapped hole 20 in a block 21.

The blocks 21 are mounted in recesses 22 in the face of the platen 14 and receive through central apertures 23 and in parallelism with the type channels, an eccentric locking shaft 24. (See Figures 11 and 12). Between the recesses 22 the supporting member 14 is provided with a clearance hole for the free rotation of the eccentric shaft 24.

One end of the shaft 24 is provided with a bearing shoulder 25 of reduced diameter where it passes through the side wall portion 26 of the supporting member and terminates beyond the latter in a square shoulder 27 to receive a locking key (not shown).

The opposite end of the shaft 24 is provided with an enlarged bearing 28 received by a counterbore 29 in the side wall portion 29a of the supporting member opposite the portion 26. (See Figure 12).

The shaft 24 is inserted from the counterbore side and through the blocks 21; in this instance three. In order to lock the shaft 24 in the proper position, I have provided the side wall portion 26 with a saw slot 30 substantially parallel with the

face of the supporting member and intersecting a second slot 31 at right angles to the slot 30 to provide a yieldable member 32. (See Figure 11).

The free end of the member 32 receives a countersunk machine screw 33 mounted in a tapped hole 33a in the supporting member 14. (See Figure 11).

Now, when the bands 1 are assembled on the studs 15 and 16 and the type channels adjusted 10 to their desired position on the supporting member, the shaft 24 is rotated by a key (not shown) to move the blocks 21 thereon within the recesses 22, and away from the studs 15, to bring the bands to a tightened position. By means of the 15 screw 33 the yieldable member will securely lock the shaft 24 in its adjusted position. (See Figure 12).

Although I have shown this type of locking means, I do not wish to be limited to the particular mechanism employed.

Having described my invention, I claim:

1. A type composition mounting comprising a supporting member, means for anchoring one end of the type chase thereto, an eccentric shaft journalled in the member, a block movably mounted in the member and embracing the eccentric shaft, and means on the block for engaging the other end of the type chase.

2. A type composition mounting comprising a supporting member having fixed studs adapted 30 to be inserted through slots in bands of a type chase, an eccentric shaft in said supporting member, blocks on said shaft, and studs projecting from said blocks and adapted to be inserted 35 through slots in the opposite ends of the chase bands.

3. A mounting for a type chase comprising a supporting member, means for removably attaching one end of the chase to said supporting member, movable blocks to which the other end of the chase is secured, said blocks being formed with longitudinal holes, and an eccentric shaft passing through said holes to move the blocks in a direction to draw the chase tight upon the securing member.

4. A mounting for a flexible type chase comprising a supporting member, means for removably attaching one end of the chase to said supporting member, the latter formed with a recess under the free edge of the chase, blocks to which the other end of the chase is secured movable in said recess to draw the chase tight, said blocks being formed with aligned holes, an eccentric shaft projecting through said holes to move the blocks in a direction to draw the chase tight upon the securing member, and means for holding the blocks in their adjusted positions.

5. A composition mounting for a type chase having a plurality of strap bands and type channels carried thereby, comprising a supporting member, fixed means for removably attaching one end of each strap band to said supporting member, the supporting member formed with a recess under the free ends of the strap bands, blocks to which said ends of the bands may be secured, movable in said recess to draw the bands tight, an eccentric shaft engaging the blocks to move them in a direction to draw the bands, and the type channels through which they pass, tight upon the securing member, and a clamping means for the shaft.

FRANK H. POEPPELMEIER.
